BICYCLE HEADLIGHT

James L. Schucker, Royal Oak, Mich., assignor, by mesne assignments, to Howell Industries, Inc., a corporation of Michigan

Filed Aug. 24, 1962, Ser. No. 71,437

Term of patent 14 years

(Cl. D48—24)

FIGURE 1 is a perspective view of a bicycle headlight embodying my new design with the fragmentary portion of a bicycle shown in dotted lines for illustrative purposes only;

FIGURE 2 is a plan view of the bicycle headlight shown in FIGURE 1;

FIGURE 3 is a side elevational view thereof;

FIGURE 4 is a bottom view thereof;

FIGURE 5 is a front elevational view thereof; and

FIGURE 6 is a rear elevational view thereof.

I claim:

The ornamental design for a bicycle headlight, as shown and described.
